UNITED STATES PATENT OFFICE.

ARTHUR F. O'LEARY, OF BERWICK, PENNSYLVANIA, ASSIGNOR TO AMERICAN CAR AND FOUNDRY COMPANY, OF ST. LOUIS, MISSOURI, A CORPORATION OF NEW JERSEY.

METAL-SHAPING DEVICE.

1,184,009.

Specification of Letters Patent. Patented May 23, 1916.

Application filed January 28, 1916. Serial No. 74,795.

To all whom it may concern:

Be it known that I, ARTHUR F. O'LEARY, residing at Berwick, Pennsylvania, and being a citizen of the United States, have invented certain new and useful Improvements in Metal-Shaping Devices, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a vertical central section of the improved metal pressing machine, showing a tank head partly formed and locked in position. Fig. 2 is a similar view illustrating the parts in the position wherein the tank head is completely formed. Fig. 3 is a composite view the upper portion being an inverted half plan of the male die, and the lower portion being a half plan view of the female die; and Fig. 4 is a side elevational view of the male die showing the gags in operative positions.

Among other types of sheet metal-forming work is that in which a flat circular disk is given an outer convexity and its circumferential border is converted into an annular flange deflected from the original plane of the disk. The deflection of the circumferential border may, if desired, be sufficient to produce a flange which forms a short cylindrical portion adapted to be slid over or into another cylinder. The tank head or tank dome head of a tank car is an example of this kind of work, requiring a so carefully formed perimetrical flange that when the head is slipped over an associated shell a fluid-tight joint may be made between them. This is in marked distinction to small-sized flanged articles in which the flange may contain wrinkles, negligible in consequence of the small dimensions of the article. Such large articles as tank heads present a serious problem in the formation

of their flanges due to the excessive buckling of the metal in the flange and contiguous portions.

This invention relates to devices for producing such products from a plane disk of any suitable material. Machines embodying it are characterized by their ability to first form an outer annular portion of the disk which may include such a flange as has been referred to, this portion being that in which the greatest amount of buckling of the material would, in old practice, take place. It has been found that, by shaping and holding this outer annular portion first, and fashioning the central portion of the disk inclosed thereby afterward, there is such a control of the material of the piece being formed that wrinkling thereof, and especially in its flange portion, is eliminated. The finished pressing is consequently ready for immediate assembly with an intended associate part without further treatment, in so far as the fit is concerned.

The construction is novel, as is the control and operation of the parts as will become evident from what follows.

Referring specifically to the drawings, A represents the lower stationary table upon which is mounted a female die comprising a base section 1, having an annular and arcuate die portion 2, a central movable female die section 3 and a supplementary female die section 4. Said base portion 1 is firmly secured to the table A by service clamps B which project through apertures in the outer wall of said base section. Supplementary female die section 4 is seated in the female die cavity and has a taper fit with the upper portion of the outer wall of the base section 1 thereby being automatically centered at the time of assembling. It is also locked in place by tap bolts 5 and contains positioning pins 6 projecting from its upper surface. The central movable female die section 3 is in the form of an inverted cone frustum and the inner annular wall of the base section 1 is conformed to it. Therefore central die section 3 is self-centering when it moves into the central cavity of base section 1.

The upper surface of the central female die section 3 is concave and has the same

curvature as the annular arcuate portion of the base female die section 2. Said arcuate portion and the concave portion of the central female die member 3 complement each 5 other and form a continuous die surface during pressing operations.

Attached to the upper movable table C is a male die member comprising a central inverted frusto-conical male die 14 integral 10 with which and surrounding the upper portion of which is a ram annulus 7 provided with an upper flange 8 bearing against the under side of table C. Other service clamps B engage flange 8 and hold the entire upper 15 male member in place. The ram annulus 7 is provided with an upwardly opening channel 9 and is perforated at 10 for the passage of bolts 11. The lower ends of said bolts depend materially below the ram annulus 7 20 and in the form illustrated are screwed in pairs into flanges 12 of outer male die segments 13 which are annularly disposed around the central frusto conical male die 14. The heads of bolts 11 are adapted to 25 act as fulcrums for the shanks of said bolts and the male die segments 13 into which they are screwed, said male segments being capable of a certain degree of oscillation. As bolts 11 enter outer male die segments 13 30 at points nearer the inner faces of the male die segments than the centers of gravities thereof, the male die segments tend to swing inwardly toward the central male die 14 whenever the male die member, as a whole, 35 is retreating from the female die. Thus a ready separation of the male and female die members is accomplished.

Each male die segment 13 is connected to the central male die member 14 by a headed 40 tie bolt or rod 15, the metal of the upright walls of the central male die 14 and outer male die segments 13 being cut away or cored out at 16 and 17, respectively, to permit of the swinging of tie bolts 15 when 45 there is relative movement between the central male die member 14 and the outer male die segments 13.

Disposed about the outer vertical face of the ram annulus 7 of the male die member 50 are gag brackets 18, each of which has been shown to contain a pair of T or other shaped slots 19. A gag 20 having an upper portion shaped to fit a slot 19 is slidably mounted in each of said slots, and is provided with a suitable operating handle. In the drawings, two gags 20 have been shown as adapted to coöperate with the flanges 12 of each outer male die segment 13, but it is to be understood that a single or any number 55 of gags may so coöperate with a single male segment 13 and a single gag bracket or one adapted to retain more than two gags may be employed according to the particular design elected for the device. When the 60 gags are arranged as shown in the draw- 65

ings, their inner ends may be slotted, as at 21, to accommodate the bolts 11 which extend into the outer male die segments 13.

The operation of the device is as follows: With the male die member positioned any 70 convenient and suitable distance above the female die member, as shown in dot and dash lines in Fig. 1, a cold circular disk E may be slid on to the upper face of the supplementary female die member 4 without particular care, it becoming accurately positioned as it drops between positioning pins 6. Gags 20 are pushed inwardly to the positions shown in Fig. 1, where each lies beneath the under surface of ram annulus 7 75 and above the upper surface of an outer male die segment 13. Tie rods 15 prevent an outward swinging of said male die segments 13 and the operator may actuate means, well known in the art, whereby ram D drives downwardly the upper table C and the male die member, as a whole, connected therewith.

Because of the interposition of gags 20 between the ram annulus 7 of the upper male die and the outer male segments 13, the latter project below the bottom curved surface of the central frusto-conical male die member 14, and the under curved faces of the outer male die segments 13 first engage the 80 upper surface of the disk E forcing the latter downwardly into the female die until the outer annular border of the disk E is principally confined between the under curved surfaces of the outer male die segments 13 and the upper arcuate surface 2 of the female base section 1. During the 85 transference of the disk E from its original upper position to that shown in Fig. 1, the more nearly circumferential border of disk E becomes upturned and shaped by the inner and outer faces of the supplementary female die member 4 and outer male die segments 13, respectively.

A flange forming a relatively short cylinder is therefore created about the perimeter of the disk E and a portion of the spherical segment that the rest of the disk is to conform to is fashioned by the under and upper 90 curved surfaces of said outer male die segments 13 and of the arcuate annular female die portion 2 of the base section 1. Up to this point the circular central disk portion surrounded by the outer male segments 13 has been unchanged, except for such tension 95 as it has been placed under. The operator then causes the ram D to act to slightly raise the table C and the entire male die member where by the gags 20 are relieved of any friction due to the compression of the male die member parts, and said gags are slid outwardly by the manipulation of the handles to occupy the positions shown in Fig. 2. Thereafter the operator again causes the 100 ram D to descend and the full pressure of the 105

actuating means being upon said ram, the central inverted frusto-conical male die member previously held from contact with the disk E is carried down to the position depicted in Fig. 2. Upon the second down stroke of the entire upper male die member, the outer male die segments 13, now freed from rigid relation with the central frusto-conical male die member 14, resume their former relation to the arcuate die annulus 2 of base section 1 and the previously formed portion of the disk E, locking said disk portion in fixed position, while the central frusto-conical male die member engages and shapes the hitherto unformed central portion of disk E. The inner faces of said outer male die segments are inclined to correspond to the inclination of the side walls of the central frusto-conical male die 14, and therefore, as male die 14 progresses downwardly it expands the ring of male die segments 13 causing the flanges of the work located between them and the supplementary female die 4 to be pressed perfectly smooth. By proper manipulation, the upper table C is returned to its initial position and the entire upper male die member resumes the position indicated in dot and dash lines in Fig. 1.

5 What I claim is:

1. In combination, a female die, a male die comprising a die annulus and a die member movable independently thereof, means for unifying and separating said die annulus and independently movable die member, and means for bringing said male and female dies together, whereby said female die and die annulus are adapted to shape a border portion of a piece of work to include a perimetrical flange and lock the same in position, said independently movable die member being adapted to subsequently shape the remainder of the work.

10 2. In combination, a female die, a male die comprising an expandable die annulus and a die member independently movable thereof, means for unifying and separating said die annulus and independent die member, and means for relatively positioning said male and female dies, whereby said female die and die annulus are adapted to shape a border portion of a piece of work to include a perimetrical flange, said independently movable die member being adapted to subsequently shape the work within its previously formed border portion.

15 3. In combination, a sectional female die, a male die comprising a die annulus and a central die member, means for unifying and separating said die annulus and central die member and means for positioning said male and female dies, whereby a portion of the latter and said annulus are adapted to form a border portion of a piece of work and lock it in position, said central die member being adapted to subsequently form the work within the border portion and a female die section being adapted to eject the finished work.

20 4. In combination, a female die comprising a plurality of sections one of which is movable, a male die comprising a die annulus and a central die member, means for unifying and separating said die annulus and central die member and means for relatively moving the dies, whereby sections of said female die and die annulus are adapted to shape a border portion of a piece of work, perimetrical flange it and lock it in position, said central die member being adapted to subsequently form the remainder of the work and said movable female die section being adapted to eject the finished work.

25 5. In combination, a male die and female die, the latter being provided with a movable die section, an elevating device therefor, means on said movable die section adapted

to coöperate with said elevating device, and means for relatively moving said male and female dies, whereby a piece of work is adapted to be formed, and removed from 5 said female die by the action of said elevating device upon said movable female die section, the latter being adapted to be tilted under the control of said elevating device and coöperating means to discharge the 10 work.

6. In combination, a male die, a female die comprising die sections one section being provided with a socket and another section being movable and adapted to be automatically 15 centered therein, an elevating device for said movable section, coöperating means on said elevating device and movable section and means relatively positioning said male and female dies, whereby a piece of 20 work is adapted to be formed, elevated by said movable section, the latter being adapted to tilt under the control of said coöperating means to discharge the work, and be returned and automatically centered in 25 its socket.

7. In combination, a female die, a male die comprising a central die member, a ram movable therewith and an expansible die annulus alined with said ram, and means 30 adapted to be interposed between said ram and annulus for unifying and separating said central die member and die annulus whereby the latter and said female die are adapted to form a border portion of a piece 35 of work to include a perimetrical flange and to apply smoothing pressure to said flange, said central die being adapted to subsequently form the work within said border portion and said die annulus being adapted 40 to retreat from the flange after the smoothing operation.

8. In combination, a female die, a male die comprising a central die member, an annularly arranged ram and annularly disposed die segments swingingly suspended 45 from said ram, and means adapted to be interposed between said ram and die segments for unifying and separating said central die member and die segments, whereby the latter 50 and said female die are adapted to form a border portion of a piece of work to include a perimetrical flange and to apply smoothing pressure to said flange, said central die being adapted to subsequently form the work 55 within said border portion and said die segments being adapted to swing away from the formed flange by gravity.

9. In combination, opposing die members 60 movable toward each other, said members being adapted to form a perimetrical flange on a piece of work and to lock said flange in a given position, one of said dies having a portion adapted to move independently of the work-locking portions of said dies to 65 shape the metal inclosed by said flange.

10. In a device of the class described, a female die, a plural-part male die having independently movable work-forming parts and means for causing said parts to act as an integer and to coöperate with said female 70 die to incompletely form and flange work and a part of said male die being adapted to act independently to complete the forming of the work.

11. In a device of the class described, a 75 female die, a male die comprising a series of die members and another die member common to said series and means for combining said series and common die members to act as an integer only capable of incompletely forming work, said common die member being adapted to complete the formation of the work after predetermined actuation of said combining means.

12. In a device of the class described, a 80 female die, a male die comprising a group of die members and an independently movable die member common to said grouped die members and means for combining said grouped and common die members to act 85 as an integer adapted to incompletely form work, said common die member being adapted to expand said grouped die members and complete the fashioning of the work after predetermined actuation of said combining means.

13. In a device of the class described, a female die, a male die comprising an expansible group of die members and an independently movable die member with 90 which said grouped die members are oscillatively connected, and means for combining said male die members to act as an integer to incompletely form work, said independently movable die member being adapted to complete the work-shaping after predetermined actuation of said combining means, and said grouped die members being adapted to swing to release the work.

14. In a device of the class described, a 95 female die, a male die comprising a plurality of die members and control means therefor adapted to lock part of said male die members in an ineffective position at certain times and render all of said male 100 die members effective at other times, said times being within the period of a single work-shaping operation.

15. In a device of the class described, a female die, a male die comprising a plurality of grouped die members and an independently movable die member and a ram extension from the latter for actuating the grouped die members.

16. In a device of the class described, a 120 female die, a male die comprising an expansible group of die members and an independently movable die member, and means for rigidly combining and for disconnecting the latter and said grouped die members to 130

cause said independently movable die member to move in unison with and independently of the grouped die members, said independently movable die member being 5 adapted to expand said grouped die members within said female die.

17. In a device of the class described, a female die, a male die comprising an expansible group of die members and an independently movable die member from 10 which said grouped die members are swingingly suspended, and means for causing all of said male die members to move in unison at certain times, said independently 15 movable die member being adapted to expand said grouped die members within said female die, the grouped die members being adapted to swing by gravity to work-releasing positions.

18. In a device of the class described, a 20 female die, a male die comprising a central die member and a plurality of die segments swingingly mounted thereon and forming a surrounding expansible die annulus, a ram extension from said central die member projecting over said segments and gags adapted 25 to be interposed between said ram extension and die segments to render said central die member ineffective and to be withdrawn to cause said central die member to 30 complete the work-forming operation.

In witness whereof I have hereunto set my hand in the presence of two witnesses.

ARTHUR F. O'LEARY.
